CLAIM

The ornamental design of the bicycle brake pad spreader tool, as shown and described.

DESCRIPTION

FIG. 1 is a front perspective view of a bicycle brake pad spreader tool.

FIG. 2 is a front elevation view of the bicycle brake pad spreader tool

FIG. 3 is a rear elevation view of the bicycle brake pad spreader tool.

FIG. 4 is a right side elevation view of the bicycle brake pad spreader tool.

FIG. 5 is a left side elevation view of the bicycle brake pad spreader tool.

FIG. 6 is a top view of the bicycle brake pad spreader tool; and,

FIG. 7 is a bottom view of the bicycle brake pad spreader tool.

The broken lines depict portions of the bicycle brake pad spreader tool in which the design is embodied that are not considered part of the claimed design.
